UNITED STATES PATENT OFFICE.

OTIS R. ANGELL, OF HAVERHILL, MASSACHUSETTS, ASSIGNOR TO HAMEL SHOE MACHINERY COMPANY, A CORPORATION OF MASSACHUSETTS.

SHOE-MACHINE.

1,339,591.

Specification of Letters Patent. Patented May 11, 1920.

Application filed November 12, 1917. Serial No. 201,524.

To all whom it may concern:

Be it known that I, OTIS R. ANGELL, a citizen of the United States, residing at Haverhill, in the county of Essex and State 5 of Massachusetts, have invented certain new and useful Improvements in Shoe-Machines, of which the following is a specification, reference being had therein to the accompanying drawings.

This invention relates to shoe machines and more specifically to machines adapted to set and burnish the edges of shoe soles.

In machines of this type it is customary to employ a plurality of operating tools 15 adapted for use in setting the shank and forepart respectively of the sole, and to provide means permitting either of such tools to be presented in position for use and positively locked in said position. In machines 20 of said type as at present commercially known, the tools are supported at the diametrically opposite sides of a pivoted tool holder, and in reversing such tool holder for alternative use of the tools it is first necessary to unlock the holder and thereafter to 25 swing the same through 180°, whereupon the holder is again locked in position.

One object of the present invention is to avoid the above awkward and time-consuming 30 operation by the provision of a single manually operated device which serves both as a locking and reversing means for the tools.

Another object of the invention is to so 35 arrange the tools that only a relatively slight movement thereof is necessary in carrying them from operative to inoperative position.

Another object of the invention is to provide, in a machine of the above type employing a vibratory tool-holding head with power driven means engaging said head for 40 vibrating the same, an adjustable wear plate or surface between said driven means and said head whereby to take up all looseness 45 of parts occasioned by wear, thus securing freedom from undesirable noise and vibration at all times.

Other and further objects of the invention 50 as well as desirable structural details and combinations of parts are set forth at length in the accompanying specification and disclosed in the drawings annexed hereto in which:—

55 Figure 1 is a perspective view of the tool-

holding head of the machine, the drive shaft and supporting parts being omitted for the sake of clearness of illustration. Fig. 2 is a sectional view through the tool-holding head at right angles to the drive shaft showing 60 the end of the drive shaft and the coöperating parts of the head. Fig. 3 is a sectional end elevation of a portion of the tool-holding head, the lower part being broken away, and Fig. 4 is a diagrammatic elevational 65 view illustrating the operative mechanism as mounted in position on the machine frame.

This invention relates to an improvement in a machine of the type described in my co-pending application Serial #201,522, filed 70 November 12, 1917, to which reference may be had for a fuller disclosure of certain basic elements of the machine.

It is believed sufficient herein to indicate at 1 a drive shaft which may be suitably 75 supported in a frame A of any desired form, said shaft being provided at its end with an eccentric pin or cam 2. Near the extreme end of shaft 1 and adjacent the pin 2 is a supporting-member 3 which may form a 80 part of the machine frame, or, if desired may be an element separate therefrom but fixed or adjustably secured thereto. Projecting from said supporting-member 3 and substantially in the horizontal plane of the 85 shaft 1, but spaced therefrom, is a pin or shaft 4, said pin being provided with a head 5. Mounted to rock upon said pin and between the head 5 and the support 3 is a tool-carrying head 6, this head being free to rock 90 in a vertical plane about the pin 4.

Projecting laterally from said head are a pair of spaced apart arms 7 and 8, said arms being located above and below the shaft 1 and embracing the same. As herein shown 95 the arm 8 is provided at 9 with a machined bearing surface. The arm 7, however, is provided centrally thereof with a slot 8' and engaging within said slot, and slidably therein in a direction lengthwise of the arm, is 100 a fin 9' projecting upwardly from a plate 10, said plate being formed as a wedge having its thicker portion adjacent the extremity of arm 7, the lower portion of said plate 10 being formed as a bearing surface opposed to 105 the surface 9. In the outer extremity of the plate 10 is formed an opening 11, through which extends a bent rod 12 having a head 13 below the plate 11 serving to prevent disengagement of the parts. A horizontal por- 110

tion 14 of the rod 12 extends through a suitably formed opening 15 in the arm 7 and is arranged for engagement by set screws 16, 17 whereby the rod may be adjustably fixed 5 in position, this arrangement permitting a minute adjustment of bearing surface 10 with respect to the surface 9.

Mounted to slide between the surfaces 9 and 10 and having a journal engagement 10 with the pin 2, is a block 18. It will now be seen that by the above construction, rotation of the shaft 1 will cause a rapid vibration of the head 6 about the pin 4 in a vertical plane, the adjustable wedge-member 15 permitting of readily compensating the bearing surfaces for wear.

The head 6 is provided with a downwardly projecting member 19 which serves as a support for the tool holders. The member 19 is chambered out to form a cavity 20 and leading into said cavity from the lower surface of said member 19 are a pair 20 of guide openings 21 and 22, within which are mounted to slide a pair of tool holders 23 and 24. These tool holders may be provided with any suitable means for holding the operating tool thereupon, such means being herein shown as comprising a spring-clip 25 for engagement with the tool, this 25 clip being of old and well known construction and no claims being made herein thereto. The tool-holding members 23 and 24 are provided at their upper portions with rack-members 26 and 27, said rack-members 25 being arranged in opposing relation. Projecting transversely through the member 19 and having bearings therein is a shaft 28, said shaft being provided at its central portion and within the chamber 20 with a 40 pinion 29, said pinion meshing with the two racks 26 and 27 respectively.

The shaft 28 projects forwardly beyond the side of the member 19, and is provided with an enlarged head 30, said head being 45 bifurcated to form opposed arms 31, 32. Passing through and fixed in said arms is a pintle pin 33 having pivotally mounted thereupon and located between said arms a lever-member 34. Upon one extremity of 50 lever 34 is mounted a finger piece in the form of a flat plate 35 although the specific form of this member is not essential to the invention. Upon the opposite extremity of the lever 34 is a latch-member 36, this latch-member being adapted for locking engagement with either of two openings 37 or 38 formed within the face of member 19, a spring 39 being provided which tends to throw the latch member 36 into locking engagement with one of said openings at all times. Upon the tool-holding members 23 and 24 are mounted a pair 60 of tools as C, D adapted for use upon the shank and forepart of the sole respectively. 65 On the top of the head at 40 may, if desired,

be provided an oil cup having a suitable passageway for oil leading to the pin 4.

The operation of this part of the invention will now be clear. At the beginning of the operation the latch-member 36 is in engagement with one of the openings, 37 for example, of the member 19, the tool holder 23 at this time being shown as in lowered position with the tool carried thereby in proper position for use. The drive 75 shaft being in rotation, the head with the tools thereon is rapidly vibrated, and as the tool carried by the member 23 for example, is the shank tool, this will be first employed. Upon reaching the forepart of the shoe, the 80 operator will place his hand or finger upon the member 35 pressing the same to disengage the latch from its corresponding opening, and at the same time will swing the lever 34 with its supporting shaft 28 into 85 a position such that the latch 36 may engage the opposite opening 38.

The turning movement of shaft 28 through engagement of pinion 29 and the racks 26 and 27 will thereby reverse the position of the tool holders, thus permitting operation upon the forepart of the shoe. At the completion of the forepart of the shoe the above operation is reversed bringing the shank tool back to initial position for 95 finishing the shoe and for beginning the operation on the succeeding shoe.

While the above disclosure is that of a preferred form of invention, it is to be understood that the present invention is not 100 limited to the details of construction shown but is to be construed as including any or all modifications of the same within the province of mechanical skill which may be embraced within the scope of the appended 105 claims.

Having thus described the invention what I desire to claim as new and to secure by Letters Patent of United States is:—

1. In a tool-holding head for edge setting 110 machines having a socket for a tool holder, a tool holder slideable in said socket and provided with a rack, a pinion meshing with said rack and means for turning the pinion.

2. In a tool-holding head for edge setting 115 machines having a socket, a tool holder slideable in said socket, and means for sliding said tool holder in its socket comprising a rotatable shaft and means for locking said shaft in either of a plurality of positions. 120

3. In an edge setting machine of the type disclosed, a pair of tools, means for supporting said tools in substantially parallel relation, and means for alternately moving said tools lengthwise to and from operative 125 position.

4. In a vibrating tool-holding head for edge setting machines, a plurality of longitudinally retractable tool holders, and means for projecting one of said tool holders to 130

operative position and for retracting another of said tool holders to inoperative position.

5. In an edge setting machine, in combination, a tool-holding head, a pair of tool holders adjustably supported therein, means for simultaneously longitudinally projecting one of said holders while retracting the other, and means for locking said holders 10 in adjusted position.

6. In combination, in a tool-holding head for edge setting machines having a pair of sockets, tool holders slidably mounted therein, the respective tool holders being provided with oppositely facing racks, a shaft interposed between said tool holders and having a pinion meshing with the racks, and means for turning said shaft.

7. In an edge setting machine, in combination, a plurality of tool holders, and means for alternately moving said tool holders in parallel paths into and locking them in operative position, said means comprising a single manually operated member.

8. In an edge setting machine, in combination, a pair of tool holders slidable to and from operative position and means for simultaneously moving said tool holders and locking the same in adjusted position, said 30 means comprising a single manually operative lever.

9. In a locking device for a retractable tool holder, a support having a plurality of openings therein, a rotatable shaft, and a 35 spring-pressed locking lever carried thereby, said lever being provided with a finger piece and having a latch element adapted to engage within one of said openings, actuation of the finger piece serving to unlock and 40 rotate said shaft.

10. In a tool-holding head for edge setting machines, having a retractable tool holder mounted therein, means for retracting and projecting said tool holder comprising 45 a rotatable shaft, a lever pivoted to the extremity of said shaft and having upon one end a finger piece and at its opposite end a latch element, and resilient means for causing locking engagement of said element with an opening in the tool-holding head.

11. A locking device for the tool holders of edge setting machines, comprising a support, a shaft rotatably mounted thereon, said shaft having a slot in its extremity, a lever 55 pivoted within said slot, a handle upon one end of said lever, a latch element upon the other end of said lever adapted for engagement with suitable openings in said support, and a spring-member tending constantly to project the latch element into locking engagement with one of said openings.

12. In an edge setting machine having a rotary drive shaft, a support, a tool-holding 65 head pivoted to rock thereon, and having opposed guiding surfaces, means for adjustably positioning one of said surfaces to take up wear, a block engaging between and 70 slidably upon said surfaces, and means for moving said block in a circular path.

13. In an edge setting machine a drive shaft having an eccentric pin thereon, a block having a journal opening engaging said pin and a tool carrying head having 75 surfaces engaging said block, one of said surfaces comprising a slidably mounted wedge-plate, and means for adjustably positioning said plate.

14. In a vibratory, tool-holding head for 80 edge setting machines, an adjustable guiding surface comprising a slidable wedge-plate having an opening in one end thereof, a member engaging within said opening, means for supporting said member for adjustment, means for fixing said member in 85 adjusted position and a driven member engaging said guiding surface for vibrating the head.

15. In an edge setting machine, a retractable tool holder, a support having a plurality of openings therein, a rotatable shaft, a locking lever carried thereby, and having a latch element adapted to engage within either of said openings, and connections between 95 said rotatable shaft and said tool holder whereby said tool holder is advanced and retracted by rotation of said shaft.

In testimony whereof I have signed my name to this specification.

OTIS R. ANGELL.
